Patented Mar. 9, 1971

220,154

STORAGE CASE FOR A MANICURIST TOOL OR SIMILAR ARTICLE

Edward A. Irelan, Lombard, Ill., assignor to Sunbeam
Corporation, Chicago, Ill.

Filed Jan. 23, 1970, Ser. No. 21,046

Term of patent 14 years

Int. Cl. D3—99

U.S. Cl. D87—1

Fig. 1.

Fig. 2.

Fig. 3.

FIG. 1 is a front perspective view of a storage case for a manicurist tool or similar article;

FIG. 2 is a top plan view thereof on an enlarged scale;

FIG. 3 is an end view, each end being a mirror image of the other end;

FIG. 4 is a front elevational view thereof on an enlarged scale;

FIG. 5 is a bottom plan view of FIG. 4; and

FIG. 6 is a rear elevation of FIG. 4.

I claim:

The ornamental design for a storage case for a manicurist tool or similar article, as shown and described.
